US00D760100S

(12) **United States Design Patent**
Gathman et al.

(10) **Patent No.:** US D760,100 S
(45) **Date of Patent:** ** Jun. 28, 2016

(54) **ELECTRICAL TESTER**

(71) Applicant: **Auto Meter Products, Inc.**, Sycamore, IL (US)

(72) Inventors: **Michael R. Gathman**, Genoa, IL (US); **John C. McMillion**, Oswego, IL (US); **Douglas W. Adams**, DeKalb, IL (US)

(73) Assignee: **Auto Meter Products, Inc.**, Sycamore, IL (US)

(**) Term: **14 Years**

(21) Appl. No.: **29/507,993**

(22) Filed: **Oct. 31, 2014**

(51) LOC (10) Cl. **10-04**

(52) U.S. Cl.

USPC **D10/78**

(58) **Field of Classification Search**

(57) CLAIM

We claim the ornamental design for an electrical tester, as shown and described.

DESCRIPTION

FIG. 1 is a front perspective view of a second embodiment of our new design;

FIG. 2 is a rear perspective view of the second embodiment of FIG. 1;

FIG. 3 is a front view of the second embodiment of FIG. 1;

FIG. 4 is a rear view of the second embodiment of FIG. 1;

FIG. 5 is a left side view of the second embodiment of FIG. 1;

FIG. 6 is a right side view of the second embodiment of FIG. 1;

FIG. 7 is a top view of the second embodiment of FIG. 1; and,

FIG. 8 is a bottom view of the second embodiment of FIG. 1.

The broken lines shown in the drawings are for illustrative purposes only and form no part of the claimed design.
